US00D970571S

(12) **United States Design Patent** (10) **Patent No.:** **US D970,571 S**
(45) **Date of Patent:** **** Nov. 22, 2022**

(54) **DOOR OPENER**

(71) Applicant: **Hangzhou Junling Technology Co., Ltd.**, Zhejiang (CN)

(72) Inventor: **Yanxia Hu**, Zhejiang (CN)

(73) Assignee: **Hangzhou Junling Technology Co., Ltd.**, Zhejiang (CN)

(**) Term: **15 Years**

(21) Appl. No.: **29/840,232**

(22) Filed: **May 26, 2022**

(51) LOC (13) Cl. **15-99**

(52) U.S. Cl.

USPC **D15/148**

(58) **Field of Classification Search**

USPC ..... D13/158, 162, 168, 170, 174; D15/143, D15/148, 149, 199; D8/400 CPC . E05F 15/00; E05F 15/63; E05F 15/73; E05F 15/75; E05F 15/77; E05F 15/603; E05F 15/611; E05F 15/614; E05F 1/00; E05F 1/002; E05F 2015/631

(57) **CLAIM**

The ornamental design for a door opener, as shown and described.

DESCRIPTION

FIG. 1 is a front, right and top perspective view of a door opener, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a cross-sectional view of the door opener of FIG. 1, taken along section line 9-9 as depicted in FIG. 3. The broken lines shown in the drawings are included for the purpose of illustrating portions of the door opener that form no part of the claimed design.

1 Claim, 9 Drawing Sheets
